Term of patent 14 years

Int. Cl. D15—02

U.S. Cl. D65—1 R

FIG. 1 is an isometric view of the front, top, and left side of an aerating pump for bait containers, showing a form of my new design, the opposite view showing no more than a rectilinear surface with tubular discharge in vertical and tubular electrical conductor cord, as indicated.

FIG. 2 is a small scale isometric view of the front, top, and right side of the aerating pump for bait containers shown in FIG. 1, as mounted in the environment of an aerating pump for bait containers, shown in broken lines which container forms no part of the claimed design.

I claim:

The ornamental design for an aerating pump for bait containers, as shown and described.
